UNITED STATES PATENT OFFICE.

JOHN WILLIAM HESS, OF KITCHENER, ONTARIO, CANADA, ASSIGNOR TO CLUETT, PEABODY & COMPANY, INC., OF TROY, NEW YORK, A CORPORATION OF NEW YORK.

FOLD-OVER COLLAR.

Application filed October 11, 1921. Serial No. 507,087.

To all whom it may concern:

Be it known that I, JOHN WILLIAM HESS, a subject of the King of Great Britain, and resident of Kitchener, in the county of Waterloo and Province of Ontario, Canada, have invented new and useful Improvements in Fold-Over Collars, of which the following is a specification.

This invention relates to the manufacture of fold-over collars and especially to the production of a soft unstarched or lightly starched collar of the fold-over type which shall be inherently stiff enough to hold its shape without wrinkling or crumpling and be economical to manufacture. In its fullest expression, my invention provides for the manufacture of a completely finished collar from two single pieces or blanks of fabric, with appropriately sewed or otherwise fastened seams and edge finishes, the operations devised in relation to the blanks of the material being such as to facilitate accurate assembly of the two parts and to maintain the accuracy of size and shape of the parts and the assembled articles, and to result in a well-fashioned article of great durability adapted to keep in shape in use.

The fabric from which the assembled blanks are cut, particularly if the collar is to be worn unstarched or only lightly starched, should be firm and stout. If heavy body is to be combined with fine texture, the fabric may be any of the known multi-ply weaves, either such as to present a simple-weave surface or a pattern, or the ribbed face pattern known as piqué; or the fabric may be of any suitable stiff woven structure, either plain or patterned.

Figs. 1, 2, 3, 4 and 8 are elevations of the same end of a blank for the top of a collar in successive stages of manufacture;

Figs. 1^a, 2^a, 3^a and 4^a are respective sections on the lines *a—a* of said Figures 1 to 4 respectively;

Figs. 5, 6 and 7 are views similar to 1 to 4 showing a modified procedure;

Figs. 5^a, 6^a, 7^a and 8^a are sections on the respective lines *a—a* of Figs. 5 to 8;

Figs. 9 and 10 are respectively elevations of the corresponding end of a band blank showing two stages of manufacture;

Figs. 9^a and 10^a are respectively sections on the lines *a—a* of Figs. 9 and 10;

Figs. 11 and 12 are respective views of one

end of the band in stages of a modified procedure for making the band;

Figs. 11^a and 12^a are respectively sections on lines *a—a* of Figs. 11 and 12;

Fig. 13 shows the same end of the collar as indicated in Figs. 5 to 8, 11 and 12, the blanks being assembled and fastened together;

Fig. 14 is a section on the line 14—14 of Fig. 13;

Fig. 15 is a perspective view of the completed collar; and

Fig. 16 is a section on the line 16—16 of Fig. 15.

The operations in making a collar may comprise cutting, for example by dieing-out the blanks from suitable cloth, folding and creasing the blanks, sewing the edge folds of the blanks, except as hereinafter specified; assembling the top blank and the band blank; and fastening together the top blank and band blank; these steps are particularly concerned with a method or procedure which will produce at the resultant stage of the manufacture a collar complete except for the buttonholes and buttons or other variable or additional features, and which will not rely upon extraneous bands or plies of fabrics, reinforcements, patches, etc. for the structural completeness of the article of manufacture produced.

For example, in the form shown in Figs. 1 to 4 and 8, and Figs. 9 and 10, one end of a suitably shaped blank for the top is shown at 1, which is first creased parallel with the edges of the cut blank at 2, 3 and 4, and at 5, parallel with the top margin 12 (which may be straight, as shown, or curved). The blank is now inwardly folded as shown in Fig. 2 along the lines of the respective creases 2, 3 and 4, the inturned edges now being sewed in place by the lines of sewed stitches 7, Fig. 3. The blank can now be placed in a suitable folding machine and the inturned and sewed edges 8, Fig. 3, turned in upon themselves as shown in Figs. 4 and 4^a, and these inturned edges fastened by an interior line of stitches 9, Fig. 8, parallel with the stitches 7.

The procedure illustrated in Figs. 5, 6 and 7 likewise results in the stage of the making of the top portion illustrated in Fig. 8, but comprises additional score marks 10, Fig. 5, upon which the blank is a second

time infolded by hand or machine, both folds being made before the production of the lines of stitches 11, Fig. 7.

In either case, the completed top portion 5 is adapted to be folded at the crease 5, and is now ready to be assembled with a suitably formed band.

Referring now to Figs. 9, 9^a and 10, 10^a 10 the band is formed of a blank having a body 20, an upper margin 21, which may be straight as shown or curved, according to 20 the pattern of the collar, and which blank comprises the integral marginal portion 22 extending around the ends and bottom of 15 the band blank. The marginal portion is shown as marked off by line 23, which may be a score line outlining the contour of the ends and bottom of the band, which may be of any desired shape, and portion 22 is 20 folded upon the body by hand or folding machine. The marginal portion 22 is now sewed down by the line of stitches 24. The stage product shown in Fig. 10 may now 25 be placed in a suitable folding machine and the edge turned in upon the body of the band all around the band. It will be observed that the upper edge 25, Fig. 12^a, above the margin 21 in the present condition 30 of the blank defines a once-turned edge, while the remainder of the blank is surrounded by a twice-turned edge fold.

If desired, the stage of the product illustrated in Figs. 12, 12^a may be reached 35 without the intermediate sewing shown at 24 in Fig. 10. For example, as shown in Fig. 11, an unscored blank may be edge turned on the line 23^a and then again edge turned to produce the stage shown in Fig. 12.

The top 1 and the blank 20 are now assembled, as shown in Figs. 13 and 14, by inserting the over-hanging edge 12 of the top beneath the once-turned edge fold 21 at the top of the band 20, by then opening the top 1 out to the position illustrated in Fig. 13, 40 and then sewing a duplicate line of stitches 26 entirely around the margins of the band 20, thus conjoining the top and band. The seam thus formed at the junction of band

and top serves not only to conjoin the parts, but to determine, without special laundry-folding, an edge or line from which the top 1 depends when the collar is worn. 50

Suitable buttonholes 27 may be sewed in the band before or after assembly to the condition shown in Fig. 13. 55

It will be observed that by the described construction the top edge of the band, as finished for assembly, provides an open pocket under the edge 21 for the entire edge 12, including the overfolded ends, of the collar top, which constitutes a tongue adapted to enter the pocket under edge 21. This facilitates assembly in correct relation, the die-cut edge of the tongue bottoming in the pocket and being positioned endwise by the 60 angle 27 of the edge-fold of the band. The junction between top and band, thus formed, provides at the corners 28 of the top, Fig. 15, a strong and durable structure at the place most exposed to wear and tearing 65 strains. It will be obvious that this tongue-and-pocket seam may be varied or reversed; for example, the pocket being formed in the top and the tongue on the band, if desired; but I prefer the illustrated structure. 70

I claim:

A fold-over collar comprising a band having one edge portion folded toward its body, and a top having one edge portion folded 80 toward its body, the said top and band being elsewhere edge-folded and the edge fold fastened down to form the outer edges of the collar, and delimit a pocket under said first-mentioned edge portion of one of the 85 parts, said first-mentioned edge portions being interlocked by one of them being in the pocket formed by the other, and fastened to each other and to the body portions respectively of said band and said top, the seam so 90 formed determining a line of fold between the band and top.

Signed by me at Kitchener, Ontario, this 4th day of October, 1921.

JOHN WILLIAM HESS.
